UNITED STATES PATENT OFFICE.

PERCY F. CHOATE, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR ATTACHING FLAP-SECURING MEANS TO ENVELOPES.

Application filed August 1, 1918. Serial No. 247,790.

To all whom it may concern:

Be it known that I, PERCY F. CHOATE, a citizen of the United States, residing at Worcester, in the county of Worcester and 5 Commonwealth of Massachusetts, have invented a new and useful Improvement in a Machine for Attaching Flap-Securing Means to Envelopes, of which the following, together with the accompanying drawings, 10 is a specification.

The present invention relates to machines used in the manufacture of that class of envelopes in which the closing flap and the body of the envelope are each provided with 15 circular washers or disks, attached thereto by eyelets; to one of these disks a cord or string is secured, with its free end adapted to be wound around the two eyelets and beneath the disks, thereby securely holding 20 the closure flap in closed position over the end of the envelope.

The invention contemplates various new principles of operation in machines of this class, and more particularly in such machines as are designed to attach the closing string or cord to the envelope. In this respect the machine of the present invention embodies certain improvements of a basic character in principle of operation over the 30 machine set forth and described in United States Letters Patent No. 923,602, issued June 1, 1909, to W. E. Swift. The invention of the present application has for one of its objects to render entirely automatic 35 the attachment of the closing string or cord, simultaneously with the attachment to the envelope of the disk or washer to which said cord is permanently secured, and furthermore, to render entirely automatic the 40 twisting or coiling of said cord beneath said washer, in order to furnish a sufficient length of cord to be gripped by the eyelet, when set. Other and further objects will be apparent as the following description proceeds, reference being had in this connection 45 to the accompanying drawings, wherein—

Fig. 1 is a view in side elevation of a machine embodying my invention.

Fig. 2 is a plan view of said machine, certain parts being shown in section.

Fig. 3 is a front view of so much of the

machine as is essential to the disclosure of its operative parts.

Fig. 4 is a plan view, on an enlarged scale, of the string feeding mechanism. 55

Fig. 5 is a sectional view, on the line 5—5 of Fig. 4.

Fig. 6 is a detail view, partly in section, of the string gripping mechanism.

Fig. 7 is a view similar to Fig. 6, showing the parts in a different position.

Like reference characters refer to like parts in the different figures.

In the drawings, 1 represents the framework of the machine, which supports the 65 various operative parts hereinafter described, and also provides suitable bearings for a main driving shaft 2. The shaft 2 is belt driven by a pulley 3, through a one-revolution clutch, not shown, of any desired 70 construction. Inasmuch as this clutch forms no part of the present invention, a detailed description thereof is deemed unnecessary, it being sufficient to state that it may be operated, at desired intervals, through a 75 treadle or other device commonly employed in machines of this class, to cause the parts to go through a single cycle of operations, each time an envelope is presented in position to have a washer and a closing cord 80 simultaneously secured thereto.

The form of machine herein shown contemplates the supplying of washers or disks from a magazine 4, by mechanism of the same character as is shown and described in 85 United States Letters Patent No. 1,131,805, dated March 16, 1915, and United States Letters Patent No. 1,274,346, dated July 30, 1918, both issued to W. E. Swift. This mechanism, which forms no part of the 90 present invention, and hence need not be described in detail, consists essentially of a washer tube 5, connected at the top with said magazine 4, and opening at its bottom against a swinging sector member 6, upon 95 which rests the lowermost of the stack of washers carried by said tube. The member 6 is pivoted at 7, Fig. 2, and is oscillated through a link 8 from a cam 9 on shaft 2, as set forth and described in the 100 aforesaid Letters Patent to Swift, Nos. 1,131,805 and 1,274,346, whereby, at each

cycle of operations of the machine, to convey a washer from tube 5 into a position directly beneath the eyelet-setting plunger of the machine.

5 For purposes of illustration, I have shown an eyelet setting mechanism of the same type as is set forth and described in the two aforesaid Letters Patent to Swift, Nos. 1,131,805 and 1,274,376, the same comprising, essentially, an eyelet chute 10 with its lower end in position to hold an eyelet beneath a spring pressed eyelet needle 11, which is adapted to remove the lowermost eyelet from the chute 10 as the plunger or 15 set 12 descends. The plunger 12 is actuated by a lever 13, pivoted at 14 to the fixed framework, and connected by a rod 15 with a cam 16 on shaft 2, this mechanism being substantially the same as shown in the 20 aforesaid Letters Patent to Swift, and forming of itself no part of the present invention. The lever 13 is provided near its pivot with a segmental gear 17 which transmits rotation to a rock shaft 18, provided 25 with teeth that mesh with those of segmental gear 17. The rock shaft 18 carries an arm 19 that is connected by a link 20 with an agitating device, such as a brush, not shown, disposed within the magazine 4 and 30 operating to sweep the washers, with which said magazine is supplied, into the top of tube 5, in a manner similar to that employed in prior machines of this class.

In combination with the well known 35 washer handling and eyelet setting devices above described, the machine of the present invention provides instrumentalities adapted for the handling of a suitable string or cord, in such a manner that coincidentally 40 with the affixing of the washer, by means of the eyelet to the material of the envelope, the cord will be securely attached and twisted or coiled beneath the washer, and then automatically cut off to a predetermined 45 length. As herein shown, these cord handling devices consist essentially of a cord feeding mechanism which draws the cord intermittently from a supply reel 21, a cord gripping mechanism which draws the cord 50 a predetermined distance through a previously formed opening in the material of the envelope, and a cord twisting mechanism which imparts a coil or turn to the cord just previous to the completion of the eyelet setting 55 operation which severs said cord.

The cord, which is unwound from a continuous supply or spool carried by the reel 21, is preferably fed downwardly through a tube 22 passing through the center of said 60 reel, and thence upwardly in a straight line, as indicated at 23, through a hollow guide member 24. The guide member 24 delivers the cord to a pair of cooperating feed rollers 25 and 26, which preferably have serrations 65 on their peripheries to prevent slippage of

the cord. The feed roller 25 is carried on a shaft 27, which is suitably journalled in a fixed supporting member 28, the latter also carrying the guide tube 24. Said shaft 27 carries on one end a gear 29, which is constantly in mesh with a larger gear 30 having an integral ratchet wheel 31. Concentric with said gear 30 and ratchet wheel 31, but capable of relative movement with respect thereto, is a rocking arm 32 carrying 75 a pawl 33 adapted to engage the teeth of said ratchet wheel. The arm 32 is connected by a link 34, Fig. 1, with a bell crank lever 35, one end of which is actuated by a cam 36 on shaft 2. A complete rotation of shaft 80 2 thus effects, through the pawl and ratchet connection above described, an intermittent rotation of the feed roller 25, with alternate periods of rest when said roller is stationary. 85

The shaft 27 of roller 25 carries a pair of similar cams 37, 37, the raised portions of which are adapted to make contact with correspondingly located disks 38, 38 on the shaft 39 of feed roll 26. This shaft 39 is 90 suitably journalled in bearings which are slidably mounted in the supporting member 28, so as to move toward and away from the fixed bearings of the shaft 27. A spring 40 yieldingly presses said slideable bearings inwardly, so as normally to hold the feed roll 26 in operative relation to the feed roll 25. However, when the raised portions of the cams 37 move into contact with the disks 38, the slideable bearings of shaft 39 are forced 95 outwardly, thereby separating the feed rolls 25 and 26, for a purpose hereinafter described.

Beyond the feed rolls 25 and 26 the cord is threaded through a fixed guide tube 41, 105 and thence upwardly through a registering aperture 42 through the center of a gear 43, the latter having a downwardly projecting neck or hub 44 by which it is journalled for rotation in the supporting member 28. As 110 shown, in Fig. 5, said neck 44 has a groove 45 which is engaged by the end of a set screw 46, to prevent axial displacement of the gear 43 while still permitting its rotation. The gear 43 carries a hollow needle 47, 115 having a side opening 48 for the exit of the cord 23, as shown in Figs. 6 and 7. The hollow needle 47 constitutes, as hereinafter described, the fixed or anvil member of the eyelet setting mechanism, for cooperation 120 with the plunger 12 and eyelet needle 11, and serves as a device for locating the flap of the envelope in proper position for the washer and cord affixing operations, said needle being entered through the previously 125 formed hole in said flap.

For drawing the cord through the side opening 48 of hollow needle 47, after the release of said cord by the feed rolls 25 and 26, the machine of the present invention 130

provides a reciprocating cord gripping and pulling mechanism, which consists essentially of a horizontally sliding member 49, Figs. 6 and 7, said member being movable 5 in ways 50 provided by the fixed framework. The member 49 is pivotally connected by a link 51, Fig. 1, with a rocker arm 52, the latter having near its center of oscillation 53 a gear segment 54, which is 10 in mesh with a similar segment 55 on an arm 56 of a bell crank lever, pivoted at 57. The other arm 58 of said bell crank lever carries a cam roll 59, which travels in the groove of a suitable cam 60 carried by shaft 2. The sliding member 49 has projecting 15 therefrom a lower fixed gripper jaw 61, and has pivoted thereto at 62 a cooperating movable upper gripper jaw 63. The latter has an elongated slot 64 to receive the end 20 of the cord 23, said slot being located at the rear of the serrated gripping portions 65, 65 of said jaws. When the upper jaw is depressed, as hereinafter described, to seize the cord between said serrated gripping 25 portions 65, 65, the ensuing rearward movement of sliding member 49 under the influence of cam 60, will draw a sufficient length of cord through the opening 48 to provide the desired fastening for the envelope. 30 The operation of the movable gripper jaw 63 is accomplished by means of a lever 66, secured to the pivot pin 62 of said jaw. One end of said lever carries a cam roll 67, which is yieldingly pressed upwardly by a spring 35 68 secured to the other end of said lever. The cam roll 67 is adapted to cooperate with an elongated cam surface provided by a rocking member 69, the latter being pivoted at 70, Fig. 7, to a bracket 70' carried by the fixed 40 framework. Said rocking member 69 is adapted to be moved intermittently through a small arc by means of a link 71, which connects it to a bell crank 72 that is actuated by a cam 73 on shaft 2. In the position of the 45 parts shown in Fig. 1, which represents the normal condition of the machine at either the commencement or the conclusion of a single cycle of operations, the gripper members 61 and 63 are separated, but are at some distance from the hollow needle 47. When a 50 cycle of operations is started, the end of the cord is fed through the opening 48 by the action of the feed rolls 25 and 26, and simultaneously therewith the member 49 moves 55 sharply forward, under the influence of the sharply inclined portion 74 of cam 60, so as to carry the jaws 61 and 63 into the position illustrated by Fig. 6. As soon as this position is reached, the cam 73 causes an elevation 60 of rocking member 69, thus permitting the jaw 63 to close, under the influence of spring 68, so that the ensuing rearward movement of member 49 will draw the cord through opening 48, as illustrated in Fig. 7. 65 The rearward movement of member 49 car-

ries the jaws into the position illustrated by dotted lines 61' and 63' in Fig. 1, a sufficient distance to provide for several inches of cord on each envelope, and before the member 49 returns to its forward position, the rocking 70 member 69 is lowered into the position shown in Fig. 1, so that the contact of cam roll 67 therewith will cause the elevation of jaw 63 and the release of the cord at the proper time. 75

The drawing out of the cord by gripper jaws 61 and 63, as above described, is preceded by the release of said cord from the feed rolls 25 and 26, which, it will be understood, have served to project the end of the cord 80 through opening 48 at the commencement of the cycle of operations. This operation carries the end of the cord through the opening in the flap of the envelope, which has previously been placed over the hollow needle 85 47, as shown at 75, Figs. 6 and 7. As the plunger 12 and needle 11 thereafter descend, carrying with them a washer and eyelet for attachment to said flap 75, the hollow needle 47 is rotated, so as to impart a turn or loop 90 to the cord of sufficient length to insure its retention between the material of the flap and the superposed washer when the eyelet is set. To this end the gear 43 is in mesh with a segmental rack 76, carried by a bell crank 95 lever 77 which is pivoted at 78 to the fixed framework. Said lever is operated through a link 79, which is connected to a bell crank 80 that is actuated by a suitable cam 81 on shaft 2. Just prior to the attachment of the 100 washer to the flap 75, and while the cord 23 remains drawn to the limit of its rearward movement by jaws 61 and 63, the gear 43 is rotated, as above described, to twist the cord the required distance around the hollow 105 needle 47. The subsequent complete descent of the plunger 12 projects the eyelet through the opening in the flap 75 and spreads it so as to secure the washer thereto, in the manner well known in eyelet setting machines of 110 this class. The twisted portion of the cord lying between the washer and the material of the flap affords sufficient material to be firmly seized and compressed by the eyelet setting operation, and as an incident to this 115 operation, the cord is cut off and severed by the lower edge of opening 48 when the lower end of the descending eyelet is forced past said edge. In other words, the cord is cut between the edge of the opening and the 120 edge of the eyelet, just before the latter is upset.

The gripping mechanism remains at the limit of its rearward movement, as illustrated by the dotted lines 49', 61' and 63', 125 Fig. 1, during the above described twisting operation of the cord, and preferably the operating cam 60 of said gripper mechanism is so shaped as to interpose a short dwell at this point in the movement of the gripping mech- 130

anism, during which dwell the twisting takes place. The cord is thus held stationary and under tension by said gripping mechanism, and consequently the twisting of said cord 5 is under the influence of the drag or resistance imposed by the unwinding of the cord from the reel or spool 21; as before stated, the cord at this time is free from the action of the feed rollers 25 and 26, and hence the 10 operation of twisting is carried out under the most advantageous conditions.

Just as soon as the twisting is completed, the cams 37, which have been operative to hold the feed rollers 25 and 26 apart during 15 the twisting operation, roll off of the disks 38, and thus allow said feed rolls to come together again at the finish of the operative stroke of pawl 33. The cord therefore is seized again in the bite of rollers 25 and 26 20 just before it is severed by the completion of the eyelet setting operation, and hence said cord is kept always under control, being thus disposed in position to be projected by said feed rolls outwardly through the needle 25 47 at the commencement of the next cycle of operations of the machine, for attachment to the flap of the next envelope that is presented. It will therefore be seen that in the 30 operation of the feeding rolls 25 and 26 there is first a feeding of the cord by said rolls, then a separation of said rolls, corresponding in duration substantially to the retraction plus the dwell of the gripping mechanism, and finally a bringing together of said 35 rolls to pinch the string again, without however feeding it, these three phases of operation occurring in each operative stroke of the pawl 33. To insure stoppage of the parts at the end of each cycle of operation, a suitable braking device is preferably employed 40 consisting as here shown of a leaf spring 82 which cooperates with a flat surface 83 of a roller 84, which is secured to the shaft 27.

I claim,

- 45 1. A machine of the class described, comprising, in combination, the following instrumentalities:—a feeding means operable on a supply of cord, to project the end of said cord between a washer and an article, means for gripping the end of said cord as projected by said feeding means, and for drawing it to a predetermined position, means for imparting a loop or turn to the portion of the cord lying between said washer and said article while the cord is held under tension by said gripping means, and means for setting an eyelet to secure the looped portion of said cord and said washer to said article.
- 50 2. In a machine for attaching a washer and a cord to an article by an eyelet, a feeding means for projecting the end of a supply of cord, a gripping means adapted to seize said end upon the release of said cord 55 by said feeding means, means for moving
- 60 3. In a machine for attaching a washer and a cord to an article by an eyelet, a feeding means for projecting the end of a supply of cord, a gripping means adapted to seize 65 said end upon the release of said cord by said feeding means, means for moving said gripping means to draw out a predetermined length from said supply of cord, means for imparting a loop or turn to a portion of said cord, and means for setting an eyelet to secure said looped portion of the 70 cord, together with a washer, to an article.
- 75 4. In a machine for attaching a washer and a cord to an article by an eyelet, a feeding means for projecting the end of a supply of cord, a gripping means adapted to seize 80 said end upon the release of said cord by said feeding means, means for moving said gripping means to draw out a predetermined length from said supply of cord, means for imparting a loop or turn to a portion of said cord as held under tension during a period of dwell in the movement of said gripping means, and means for setting an eyelet, to sever said cord and secure said looped portion, together with a washer, to an 85 article.
- 90 5. In a machine of the class described, a pair of cooperating rolls for feeding the end of a supply of cord, gripping means adapted to seize said end, means for separating said rolls upon the seizure of said cord by said gripping means, means for imparting a loop or turn to a portion of said cord as held under tension by said gripping means, said separating means permitting re-engagement of 95 said cord by said rolls after said loop has been formed therein.
- 100 6. In a machine of the class described, the combination with eyelet setting mechanism adapted to sever a cord and secure it, together with a washer, to an article, of means for drawing out the end of a supply of cord and holding it under tension, means for imparting a turn or loop to the portion of the cord that is to be secured by the eyelet to 105 the article, and a feeding means adapted to engage said cord before it is cut off by said eyelet setting mechanism.
- 110 7. In a machine of the class described, the combination with eyelet setting mechanism adapted to sever a cord and secure it, together with a washer, to an article, of gripping means for drawing out the end of a supply of cord and holding it under tension, means for imparting a loop or turn to the 115 cord during a period of dwell in the movement of said gripping means, and means for engaging said cord on the other side of said loop or turn before the severance of said cord by said eyelet setting mechanism.
- 120 8. In a machine of the class described, the combination with eyelet setting mechanism for attaching a washer to an article by means of an eyelet, of means for feeding a cord, and means, operable upon the release of said cord by said feeding means, for disposing a portion thereof in substantially concentric relation to the eyelet, to be gripped when said eyelet is set.
- 125 9. In a machine of the class described, the

combination with eyelet setting mechanism for attaching a washer to an article by means of an eyelet, of means for feeding a cord, means, operable upon the release of said cord by said feeding means, for drawing out said cord and holding it under tension, and means, operable in a period of dwell in the movement of said drawing and holding means, for disposing a portion of said cord in substantially concentric relation to the eyelet, to be gripped thereby when said eyelet is set.

Dated this 30th day of July, 1918.
